UNITED STATES PATENT OFFICE.

EDWARD H. BINNS AND RALPH H. BINNS, OF PITTSBURGH, PENNSYLVANIA, AND WILLIAM A. DE HART, OF TEANECK, NEW JERSEY; SAID DE HART ASSIGNOR OF HIS ENTIRE RIGHT TO SAID EDWARD H. BINNS AND SAID RALPH H. BINNS.

FLEXIBLE CLOSURE.

Application filed July 5, 1924. Serial No. 724,355.

To all whom it may concern:

Be it known that we, EDWARD H. BINNS, citizen of the United States, and resident of Pittsburgh, county of Allegheny, State of

5 Pennsylvania, RALPH H. BINNS, citizen of the United States, and resident of Pittsburgh, county of Allegheny, State of Pennsylvania, and WILLIAM A. DE HART, citizen of the United States, and resident of Teaneck, county of Bergen, State of New Jersey, have invented certain new and useful Improvements in Flexible Closures, of which the following is a specification.

The present invention relates to improvements in the type of flexible closures illustrated in an application filed by the said Edward H. and Ralph H. Binns December 21st, 1923, Serial No. 682,022, in which there are two flexible strips or stringers carrying interlocking fastening devices and a sliding cam device for moving said fastening devices into and out of interlocking engagement.

25 The interlocking fastening devices of the present invention are similar to those of the above named application, in that each comprises a metal body formed with an unobstructed upper face, a narrow rounded neck and a forked hook projecting away from the unobstructed face. The improved interlocking fastening devices are made slightly longer than those in the above named application and are formed between their ends with controlling riding lugs finished upon

30 both their inner and outer edges to operate in controlling grooves of the cam slider.

The slider consists of the spaced fore-plate and back-plate having the fastener receiving channels between them. The fore-plate and the back-plate are each formed with inwardly presented grooves running parallel in the lower portion of the slider and diverging at the upper portion thereof, the inner surfaces of the center ribs of the fore-plate and back-plate between said controlling grooves serving as guide faces which engage the side edges of the fastening devices and positively confine them in their locking plane as they are moved into interlocking engagement. The diverging grooves positively move the hooks inwardly and outwardly and change their angular positions in causing the locking and unlocking, while the guiding center ribs between the grooves

prevent any interference of the hook members with the slider, or with each other, so that accuracy of movement in the operation of the fastening members is assured.

A further feature of the present invention consists in the novel arrangement of stops to limit the closing movement of the slider upon the series of interlocking fastening devices. These stops comprise elements secured upon the flexible strips or stringers at the upper edges of the two series of fastening devices, serving to brace the upper fastening devices against accidental displacement from the strain applied to them, and each stop having riding lugs similar to those upon the fastening devices which pass into the controlling grooves of the slider and in addition stop lugs which pass outside of the edge walls of the slider in position to engage butt lugs on the fore-plate or back-plate or both. By this arrangement of stops, the slider can be moved to the extreme upper limit of the series of fastening devices, so as to cause all of said devices to be interlocked, the locking and interlocking movements being positively effected by the controlling grooves so that it is unnecessary to leave the upper series of devices disengaged as in prior devices.

The slider is provided with a swivel plate pivoted on the center of the binding post to move laterally upon its pivot into position above the slider. The swivel plate is provided with a clutch engaging between its end and the lower end of the fore-plate, so that when in normal position upon the fore-plate it will be held against outward strain when a downward pull is exerted in the unlocking movement. Pivoted upon the lower end of the swivel plate is a latch plate which constitutes a pull member by which the slider is moved upwardly or downwardly upon the interlocking devices. The latch plate is formed with side flanges that embrace the sides of the swivel plate and fore-plate to hold the swivel plate against accidental lateral movement upon its pivot. The latch plate is further provided with angular side walls at its upper end that closely fit over the shaped ends of the slider and swivel plate and extend across the upper ends of the grooves of the slider to prevent downward displacement of the slider upon the interlocking devices. A spring snap set

projects through the bridge wall of the slider in position to engage a recess in the end flange of the latch plate for holding the same in closed position. The construction of the latch plate is such that it can also be closed upon the slider at any intermediate position, in which case the angular side walls of the latch plate will pass between adjacent interlocking members of the stringer and effectively prevent the movement of the slider in either direction upon the interlocking members.

In order that the invention may be fully understood it will first be described with reference to the accompanying drawings and afterwards more particularly pointed out in the annexed claims.

Figure 1 is a front elevation of a portion of the flexible closure embodying the present invention;

Figure 2 is a rear view of the same;

Figure 3 is a front view of the same showing the latch plate in open downwardly projecting position;

Figure 4 is a similar view showing the swivel plate and latch plate shifted slightly to one side, and indicating in dotted lines said members shifted to their operative position above the slider;

Figure 5 is a sectional view taken in the plane of the stringers on line 5—5 of Figure 7, showing the parts in closed position;

Figure 6 is a similar view with the closure parts in open position;

Figure 7 is a detail side elevation of the device as shown in Figure 1;

Figure 8 is a vertical longitudinal sectional view of the slider detached from the stringers;

Figure 9 is a detail sectional view taken on the line 9—9 of Figure 3 showing one of the stop members upon a stringer;

Figure 10 is a transverse sectional view taken on the line 10—10 of Figure 2;

Figure 11 is a vertical sectional view taken on the line 11—11 of Figure 6;

Figure 12 is a sectional view of the slider taken on the line 12—12 of Figure 8;

Figure 13 is an upper end view of the slider with the latch plate omitted;

Figure 14 is a view similar to Figure 8 showing a slight modification;

Figure 15 is a view similar to Figure 7 showing a modification of the arrangement of stops;

Figure 16 is a view similar to Figure 5 showing a further modification of stops; and

Figure 17 is a detail transverse sectional view taken on the line 17—17 of Figure 16.

In constructing the flexible closure of the type to which the present invention relates, two flexible strips or stringers, such as indicated at 1 and 2, are formed at their inner edges with beads or thickened portions 3 and

tening devices. These flexible tapes or stringers with beaded inner edges may be formed in any suitable way, but we prefer to form the bead or thickened edge by centrally folding a wide tape back and forth upon itself in accordance with the invention set forth in the application of William A. De Hart, Serial No. 678,663, filed December 5th, 1923, for improvements in flexible closures. 75

Each of the stringers 1 and 2 is provided on its inner thickened edge with a series of fastening devices which are adapted to interengage for the purpose of locking together the two stringers. The interlocking fastening devices, all of which are of the same construction, are preferably made of sheet metal blanks with U-shaped yokes 10 that embrace and are firmly compressed upon the beaded or thickened edge of the flexible tape or stringer, a narrow neck 12 having a rounded upper face, and a bifurcated or forked hook 13 projecting downwardly from the upper unobstructed face of the fastening devices. 80

Each fastening device is provided between its yoke 10 and forked hook 13 with lugs or shoulders 15 projecting oppositely from the body adjacent to the narrow neck and located when fastened upon the stringer in alignment with the beaded edge of the stringer. The specific form of the preferred fastening devices is similar in general construction and operation to those set forth in our above named application Serial No. 682,022, their proportions being slightly altered and the controlling lugs 15 being finished upon both their inner and outer edges to engage inner and outer walls of the controlling grooves of the operating slider. The fastening devices are mounted upon the stringers in suitable spaced relation so as to present the fastening devices alternately in the two series to permit them to alternately interlock within the channelled and grooved controlling slider. 95

The operating cam slider is made up of a back-plate 20 and a fore-plate 21 mounted in spaced relation upon a binder post 22 of triangular cross-section, as shown particularly in Figures 5, 6, 12 and 16 of the drawings. The binder post 22 has reduced angularly faced ends which are riveted in suitable openings in the back-plate and fore-plate for rigidly securing the plates together adjacent their upper end. The upper ends of the back-plate and fore-plate are further rigidly united by a bridge 23. The spaced relation between back-plate 20 and fore-plate 21 provides the fastener receiving channels of the controlling slider. The inner faces of the back-plate and fore-plate (constituting the walls of the slider channels) are formed with controlling grooves 25 which run parallel to the lower portion of each plate and diverge or spread apart to 100

4 for the attachment of the interlocking fas-

ward their upper end. The channel face of each of these plate portions of the slider between the controlling grooves constitutes a center rib 26, forming guide faces for the engagement and guiding of the side prongs of the forked hooks 13 of the fastening devices. The slider channels are open at the side edges to permit the passage of the fastening devices attached to the stringers.

Pivoted at 30 upon a projecting stud of the binder post 22 is a swivel plate 35 of the same general contour as the slider. This swivel plate is adapted to move laterally upon its pivot from a position parallel with the slider, as shown in Figure 3, to a position extended above the slider, as shown in dotted lines in Figure 4. When the swivel plate is in the position shown in Figure 3, it is held against outward strain away from the slider by means of an undercut lip 36, which engages the bevelled lower end 37 of the fore-plate 21 shown particularly in Figure 8 of the drawings. This means of engagement constitutes a clutch for holding the parts in desired position when a downward pull is made upon the slider through the swivel plate. The clutch is so arranged that the swivel plate is free to move upon its pivot from its normal position into its extended position above the slider. A slightly different form of this clutch engagement between the swivel plate and fore-plate is shown in Figure 14 of the drawings, in which an undercut lip 38 engages the bevelled lower edge 39 of the swivel plate. This modification is a mere reversal of the elements of the clutch shown in Figure 8.

Mounted upon the lower edge of the swivel plate is a latch plate 40 connected to the swivel plate by a hinge pin 40^a which permits the latch plate to be moved from a position parallel with and against the swivel plate, as shown in Figure 1, to a position extended below the swivel plate, as shown in Figure 3. The latch plate 40 is formed with side flanges 41, which closely embrace the edges of the swivel plate 35 and fore-plate 21 when in the position shown in Figures 1 and 7 to prevent lateral movement of the swivel plate upon its pivot. The latch plate 40 is also provided with the angular flanges 42 connected across the end by flange 43, which are shaped to fit over the upper ends of the back-plate, fore-plate and swivel plate, the flanges 42 in this position extending across the upper outwardly flaring ends of grooved controlling channels 25 of the slider to prevent the passage in either direction of the fastening devices and stop members (hereinafter referred to). A snap set 45 formed of a suitable bent piece of spring wire is mounted in a groove in the upper edge of the binder post 22 with its spring catch portion projecting through a narrow slot 46 in

bridge 23 of the slider. This snap set 45 engages a recess 47 formed in the inner wall of flange 43 and serves to retain the latch plate 40 in locking position upon the slider. Latch plate 40 has a thumb tip 40^b by which the latch plate is moved from closed to open position.

The two series of interlocking fastening devices are secured together at the lower end by a coupling 50 shown in detail in Figure 11 of the drawings. This coupling embraces the interlocking forked hooks at the lower end of the two series of fastening devices and prevents separation of the closure at this point. It will be understood that the coupling 50 is made of a compressible U shaped piece of metal suitably recessed upon the inner faces of its arms to fit over and securely engage the last two pairs of interlocked fastening devices. The coupling 50 also serves as the lower stop for limiting the downward or opening movement of the slider upon the interlocking devices.

To limit the upward or closing movement of the slider upon the interlocking devices, we provide at the upper end of each series of said devices a suitable stop member that cooperates with butt lugs projecting exteriorly from the slider. In the preferred form of these stop members, shown in Figures 2, 3, 9 and 10, a yoke shaped metal piece 55 is formed with oppositely presented lugs 56 adapted to travel in the controlling grooves 25 of the slider and a stop lug 57, which is presented just outside of the edge 100 of the slider back-plate in position to contact with the butt lug 58 formed integral with said back-plate. In Figures 16 and 17 a slight modification of the stop members is shown in which a U-shaped member 60 having connected yokes is clamped upon the beaded edge of the stringer and formed with duplicate riding lugs 61 traveling in controlling grooves 25, and a stop lug 62 which is presented outside of the slider in position 110 to engage the butt lug 58 on back-plate 20. These stop members 57, or 62, or equivalents of them, are preferably clamped upon the beaded edges of the stringers 1 and 2 at the upper end of each series of fastening members, so as to not only act as stops but also to brace the rows of fastening devices upon the stringers and prevent them from being accidentally forced out of place. The stop lugs upon the stop members may be presented upon both the inner and outer faces of the stringers to engage with butt stops upon both the back-plate and fore-plate as shown in Figure 15 of the drawings. The relative position of the stops upon the 125 stringers and slider can be arranged to arrest the slider at the desired point upon the interlocked fastening devices. With this arrangement of stops it is possible to move the slider to a sufficient extent upon the 130

fastening devices to cause the interlocking of all of said devices including the last member at the top of the series. This result is possible because the control of the 5 fastening devices in moving out of and into locking engagement is entirely by reason of the sliding engagement of the lugs of the fastening devices within the controlling grooves of the slider. This control clearly 10 distinguishes over similar devices in the prior art in which the unlocking or separating action upon the fastening devices has been through the spreading action of the binder post, which necessitates leaving several 15 of the upper fastening members slightly spread apart for the entry of the spreading member. The center ribs between the controlling grooves serve the important purpose of guiding the bifurcated hooks of the 20 fastening devices into their locking plane and by thus limiting the interior spaces or channels of the slider through which said hooks pass, prevent the interlocking members from becoming jammed, when the 25 slider is moved over them to cause them to lock. This guiding action is clearly shown in Figure 10 of the drawings. The upper edges of these center ribs or guide faces 26 are bevelled slightly to facilitate the entry 30 of the locking devices into the slider channels on the closing action of the slider.

The improved closure is shown in closed locked position in Figures 1 and 2 of the drawings, the engagement of the stop members 35 upon the stringers with the butt lugs upon the slider limiting the upward movement of the slider, while the presence of the angular flanges 42 of the latch plate across the upper ends of channels and grooves effectively 40 prevents the accidental downward motion of the slider. In opening the closure the latch plate 40 is pulled forward upon its hinge into the position shown in Figure 3 and with said latch plate as a pull member 45 the slider is pulled downwardly upon the interlocking devices for unlocking and separating them. The downward movement of the slider is arrested by engagement with the coupling bottom stop 50.

In this downward opening motion of the slider the swivel plate is held in close contact with the fore-plate of the slider by the clutch 36, 37. When it is desired to effect the closing of the closure, the swivel plate 55 35 and latch plate 40 are moved from the position shown in Figure 3 to the position indicated in dotted lines in Figure 4 and by an upward pull the slider is caused to move to its upper position (or any intermediate 60 position if only a partial closing is desired), and then the swivel plate and latch plate are returned to their normal positions with the latch plate held in closed position by the snap set.

The improved closure is not only of great

value because of its effectiveness as a closure device and of its simplicity and accuracy of operation, but the structure lends neatness and attractiveness to the general appearance of this type of flexible closure.

We claim:

1. In a flexible closure or fastener, the combination with flexible stringers carrying spaced interlocking fastening devices formed with riding lugs or shoulders, of a channeled operating slider formed with controlling grooves engaging said riding lugs or shoulders and positively controlling the movements of the fastening devices in both the interlocking and unlocking operations. 75
2. In a flexible closure or fastener, the combination with flexible stringers, and spaced interlocking fastening devices mounted upon said stringers and formed with riding lugs or shoulders between their ends, of a channeled operating slider formed with controlling grooves engaging said riding lugs or shoulders and positively controlling the movements of the fastening devices in both the interlocking and unlocking operations. 80
3. In a flexible closure or fastener, the combination with flexible stringers carrying spaced interlocking fastening devices formed with riding lugs or shoulders, of a channeled operating slider formed with controlling grooves engaging said riding lugs or shoulders and positively controlling the angular movements of the fastening devices in both the interlocking and unlocking operations, and a stop member secured to one of said stringers and formed with a riding lug adapted to enter a slider groove and a stop lug to engage an exterior part of said slider. 95
4. In a flexible closure or fastener, the combination with flexible stringers carrying spaced interlocking fastening devices, and an operating slider operating upon and controlling the movements of said fastening devices, of a stop lug upon at least one of said stringers, and an exterior butt lug upon said slider adapted to engage said stop lug. 100
5. In a flexible closure or fastener, the combination with flexible stringers carrying spaced interlocking fastening devices, and an operating slider operating upon and controlling the movements of said fastening devices, of a combined coupling and bottom stop embracing and securing the interlocked fastening devices at the end of the stringers in the path of the slider. 115
6. In a flexible closure or fastener, the combination with flexible stringers carrying spaced interlocking fastening devices, and an operating slider operating upon and controlling the movements of said fastening devices, of a U-shaped coupling member formed with recessed arms embracing and securing the interlocked fastening devices 120
- 125
- 130

- at the end of the stringers in the path of the slider and serving as a bottom stop for the slider.
7. In a flexible closure or fastener, the combination with flexible stringers carrying spaced interlocking fastening devices formed with oppositely extending riding lugs or shoulders, of a channeled operating slider comprising two rigidly attached spaced plates formed upon their inner faces with cooperating grooves which engage the riding lugs or shoulders of said fastening devices and positively control the movements of the same in both the interlocking and unlocking operations.
8. In a flexible closure or fastener, the combination with flexible stringers carrying spaced interlocking fastening devices formed with interengaging free ends and oppositely presented riding lugs or shoulders between their ends, of a channeled operating slider comprising two rigidly attached spaced plates formed upon their inner faces with cooperating grooves which engage the riding lugs or shoulders of said fastening devices and positively control the movements of the same in both the interlocking and unlocking operations.
9. In a flexible closure or fastener, the combination with flexible stringers carrying spaced interlocking fastening devices formed with oppositely presented riding lugs or shoulders, of a channeled operating slider comprising two rigidly attached plates, and a spacing binder post, said plates being formed with cooperating internal grooves which engage said riding lugs or shoulders and positively control the movements of said fastening devices in both the interlocking and unlocking operations independently of said spacing binder post.
10. In a flexible closure or fastener, the combination with flexible stringers carrying spaced interlocking fastening devices formed with oppositely presented riding lugs or shoulders, of a channeled operating slider comprising two rigidly attached plates, and a spacing binder post, said binder post having reduced angularly faced ends fitting and expanded in corresponding shaped openings in said plates, and said plates being formed with cooperating internal grooves which engage said riding lugs or shoulders and positively control the movements of said fastening devices in both the interlocking and unlocking operations independently of said spacing binder post.
11. In a flexible closure or fastener, the combination with flexible stringers carrying spaced interlocking fastening devices formed with interlocking ends and riding lugs or shoulders, of a channeled operating slider comprising two rigidly attached spaced plates, each plate being formed upon its inner face with controlling grooves to engage said riding lugs or shoulders, and a guiding surface between said grooves to engage and guide said interlocking ends.
12. In a flexible closure or fastener, the combination with flexible stringers carrying spaced interlocking fastening devices formed with interlocking hooks upon their free ends and riding lugs or shoulders between their ends, of a channeled operating slider comprising two rigidly attached spaced plates, each plate being formed upon its inner face with controlling grooves to engage said riding lugs or shoulders, and a guiding center rib to engage and guide said interlocking hooks.
13. In a flexible closure or fastener, the combination with flexible stringers carrying spaced interlocking fastening devices formed with interlocking hooks upon their free ends and riding lugs or shoulders between their ends, of a channeled operating slider comprising two rigidly attached spaced plates formed upon their inner faces with upwardly diverging controlling grooves to engage said riding lugs or shoulders, and an upwardly expanding guiding center rib to engage and guide said interlocking hooks.
14. In a flexible closure or fastener, the combination with flexible stringers carrying spaced interlocking fastening devices having interlocking ends and riding lugs or shoulders between their ends, of a channeled operating slider formed of rigidly attached spaced plates having grooves cut in their inner faces and receiving said riding lugs or shoulders to positively control the movements of the fastening devices in both unlocking and interlocking operations.
15. In a flexible closure or fastener, the combination with flexible stringers carrying spaced interlocking fastening devices, of an operating slider engaging and controlling said fastening devices, and a swivel plate mounted upon said slider upon a pivot perpendicular to the face of said slider and movable laterally upon its pivot to extend either above or below its pivot upon the slider.
16. In a flexible closure or fastener, the combination with flexible stringers carrying spaced interlocking fastening devices, of an operating slider engaging and controlling said fastening devices, a swivel plate pivoted upon said slider and movable laterally upon its pivot parallel with the face of said slider to extend either above or below its pivot upon the slider, and means for securing said swivel plate against movement upon the slider.
17. In a flexible closure or fastener, the combination with flexible stringers carrying spaced interlocking fastening devices, of an operating slider engaging and controlling said fastening devices, a swivel plate pivoted upon said slider adjacent to one end and

movable laterally upon its pivot to extend either above or below its pivot upon the slider, and a clutch connecting the free end of said swivel plate with the end of the 5 slider furthest away from said pivot.

18. In a flexible closure or fastener, the combination with flexible stringers carrying spaced interlocking fastening devices, of an operating slider engaging and controlling

10 said fastening devices, a swivel plate pivoted upon said slider adjacent to one end and movable laterally upon its pivot to extend either above or below its pivot upon the slider, a clutch connecting the free end of 15 said swivel plate with the end of the slider furthest away from said pivot to prevent outward strain upon said swivel plate, and means for securing said swivel plate against lateral movement upon its pivot.

20 19. In a flexible closure or fastener, the combination with flexible stringers carrying spaced interlocking fastening devices, of an operating slider engaging and controlling said fastening devices, a swivel plate pivoted 25 upon said slider and movable laterally upon its pivot to extend either above or below its pivot upon the slider, and a clutch between said swivel plate and slider consisting of an undercut lip upon one of said members and 30 a bevelled tongue upon the other of said members.

20 20. In a flexible closure or fastener, the combination with flexible stringers carrying spaced interlocking fastening devices, of 35 an operating slider engaging and controlling said fastening devices, a swivel plate pivoted upon said slider and movable laterally upon its pivot to extend either above or below its pivot upon the slider, and a latch plate 40 hinged to said swivel plate and engaging said slider for holding the swivel plate against accidental displacement.

21. In a flexible closure or fastener, the combination with flexible stringers carrying 45 spaced interlocking fastening devices, of an operating slider arranged to control said fastening devices, a swivel plate pivoted upon said slider and movable laterally upon its pivot to extend either above or below its 50 pivot upon the slider, and a latch plate hinged to said swivel plate and formed with the swivel side flanges adapted to embrace the swivel plate and slider when the latch plate is folded over upon the same.

55 22. In a flexible closure or fastener, the combination with flexible stringers carrying spaced interlocking fastening devices, of an operating slider controlling said fastening devices, and two folding members hinged 60 together and having swivel connection with said slider.

23. In a flexible closure or fastener, the combination with flexible stringers carrying spaced interlocking fastening devices, of an 65 operating slider engaging and controlling

said fastening devices, a swivel plate pivoted upon said slider and movable laterally upon its pivot to extend either above or below its pivot upon the slider, a clutch connecting the free end of said swivel plate with the end of the 70 slider furthest away from said pivot, and a latch plate hinged to said swivel plate and engaging said slider for holding the parts in locked position.

24. In a flexible closure or fastener, the 75 combination with flexible stringers carrying spaced interlocking fastening devices, of an operating slider engaging and controlling said fastening devices, a swivel plate pivoted upon said slider adjacent to one end and 80 movable laterally upon its pivot to extend either above or below its pivot upon the slider, a clutch connecting the free end of said swivel plate with the end of the slider furthest away from said pivot, and a latch 85 plate hinged to the lower end of said swivel plate and formed with side flanges adapted to embrace the swivel plate and slider when the latch plate is folded over upon the same.

25. In a flexible closure or fastener, the 90 combination with flexible stringers carrying spaced interlocking fastening devices, of an operating slider engaging and controlling said fastening devices, and a latch plate connected to said slider and formed with flanges 95 adapted to fit over the end of the slider and extend across the slider channels to prevent movement of the slider upon the fastening devices.

26. In a flexible closure or fastener, the 100 combination with flexible stringers carrying spaced interlocking fastening devices, of an interiorly channelled operating slider mounted upon said fastening devices, a latch plate movably mounted upon the slider and 105 formed with flanges arranged to embrace the ends of the slider and close the open ends of its channels, and a snap set carried by the slider in position to engage and hold the latch plate in closed position.

27. In a flexible closure or fastener, the combination with flexible stringers carrying spaced interlocking fastening devices, of an interiorly channelled operating slider mounted upon said fastening devices, a slider controlling latch plate movably mounted upon the slider, a snap set upon the slider engaging the latch plate, and a thumb tip upon the latch plate.

28. In a flexible closure or fastener, the 120 combination with flexible stringers carrying spaced interlocking fastening devices, of an interiorly channelled operating slider mounted upon said fastening devices, a latch plate connected with the slider and formed with flanges arranged to embrace the ends of the slider and close the open ends of its channels, and a spring snap set mounted in the end of the slider in position to engage the latch plate.

29. In a flexible closure or fastener, the combination with flexible stringers carrying spaced interlocking fastening devices, of a channelled operating slider comprising two rigidly attached spaced plates, a spacing binder post securing said plates and formed with a spring receiving groove, a spring snap set mounted in the groove of said binder post, and a slider controlling latch plate movably mounted upon the slider and engaged by said snap set.
30. In a flexible closure or fastener, the combination with flexible stringers carrying spaced interlocking fastening devices, of an operating slider comprising two rigidly attached spaced plates, a spacing binder post securing said plates and formed with a spring receiving groove, a bridge plate connecting said spaced plates at one end, said bridge plate having a snap receiving slot, a spring snap set mounted in the groove of said binder post and projecting through the slot of said bridge plate, and a slider controlling latch plate movably mounted upon the slider and engaged by said snap set.
31. In a flexible closure or fastener, the combination with flexible stringers carrying spaced interlocking fastening devices, a controlling grooved slider operating upon said fastening devices, a stop member secured to at least one of said flexible stringers at the upper end of a series of fastening devices, said stop member being formed with riding lugs which ride in the slider grooves and a stop lug which is presented exteriorly of the slider, and a butt lug or shoulder projecting externally from the slider in position to engage said stop lug.
32. In a flexible closure or fastener, the combination with flexible stringers carrying spaced interlocking fastening devices, a controlling grooved slider operating upon said fastening devices and provided with external butt lugs, and stop members secured to said flexible stringers and formed with riding lugs operating in the slider grooves and stop lugs which are presented exteriorly of said slider and engage said butt lugs.
